United States Patent Office.

E. H. ASHCROFT, OF LYNN, MASSACHUSETTS.

Letters Patent No. 76,878, dated April 21, 1868.

IMPROVEMENT IN STEAM SAFETY-VALVES.

The Schedule referred to in these Letters Patent and making part of the same.

TO ALL WHOM IT MAY CONCERN:

Be it known that I, E. H. ASHCROFT, of Lynn, county of Essex, and State of Massachusetts, have invented a new and improved Safety-Valve for Steam-Boilers; and I do hereby declare that the following is a full and exact description thereof, reference being had to the accompanying drawings, and to the letters of reference thereon, in which like parts are represented by like letters in the several figures.

The nature of my invention consists in a new and improved safety-valve for steam-boilers, to be hereafter described.

To enable others skilled in the art to make and use my invention, I will proceed to describe its construction and operation.

In the drawings, Figure 1 represents a half section of my invention, as also a half elevation of the same, A being the former and B the latter. The valve entire, as shown and to be described, is to be screwed or otherwise secured to its seat to permit the steam to enter the same at *x*. *a* is a hollow base, which is connected with the boiler or other vessel in which steam is generated. Screwed into *a* are two screwed standards *b b* at *e*.

The tops of these standards carry a cross-piece, *d*, slipping over the same, resting upon nuts *e e*, screwed down upon said standards. Above said cross-piece *d* there are two other nuts *f f*, corresponding to the lower nuts *e e*, and clamping said cross-piece between said nuts. Through this cross-bar passes a rod, of any suitable shape, *c*, connected with a valve, *D*, passing down through the hollow chamber *a*, and the guide-piece *g* secured to *a*. The valve or cover *D* is attached to the central rod *c*, and rests upon the valve-seat *E*. Between the valve or cover *D*, and the cross-piece *d* above, there is a strong spiral spring, *F*, pressing upon both. I perforate the valve-seat *E* by an elbow-orifice, *h*, as seen in the several figures, particularly fig. 1. This spiral spring *F* tends to keep the cover or valve *D* down upon its seat *E*, which rests upon *a*.

The operation is as follows: The tendency of the spring *F*, confined between *D* and *d*, is to press the former down upon its seat *E*. Of course, said valve-cover *D* can only be raised to permit the escape of steam by the force of said steam overcoming the strength of the spring *F*. The steam presses upon the base of *D*, and when it is strong enough to raise said valve or cover to a partial extent, it issues through those elbow-apertures *h* in valve-seat *E*, increasing the power of the surplus steam, and securing greater safety. After a sufficient escape of steam, the valve-cover *D* resumes its normal condition, and the steam generated performs its function in safety.

The pressure upon the valve-cover *D*, which the steam is to overcome, is to be regulated by the depression or elevation of the cross-bar *d*, through the double sets of nuts *e* and *f* acting on the spring *F*.

Having thus described my invention, what I claim as new, and desire to secure by Letters Patent of the United States, is—

The valve-seat *E*, with its elbow-orifices *h*, in combination with valve-cover *D*, rod *c*, and spring *F*, or its equivalent, arranged, constructed, and operated in the manner as shown and described, and for the purpose set forth.
